CLAIM

The ornamental design for a display screen with graphical user interface, as shown and described.

DESCRIPTION

FIG. 1 is a front perspective view of a display screen with graphical user interface showing a first image in the sequence on a non-claimed mobile device.

FIG. 2 is a front view of the first image in the sequence of the design shown in FIG. 1, shown removed from the non-claimed environment for clarity.

FIG. 3 is a front view of a second image thereof.

FIG. 4 is a front view of a third image thereof.

FIG. 5 is a front view of a fourth image thereof.

FIG. 6 is a front view of a fifth image thereof.

FIG. 7 is a front view of a sixth image thereof.

FIG. 8 is a front view of a seventh image thereof; and, FIG. 9 is a front view of an eighth image thereof.

The appearance of the image sequentially transitions between the images shown in FIGS. 2-9. The process or period in which one image transitions to another forms no part of the claimed design.

The uneven-length broken lines illustrate a non-claimed boundary of the display screen with graphical user interface. The outermost even-length broken lines illustrate a mobile device, which is the environment of the design, and form no part of the claimed design. The remaining broken lines illustrate portions of the graphical user interface that form no part of the claimed design.
